UNITED STATES PATENT OFFICE.

FRANK BOGART TOWNSEND, OF PENN YAN, NEW YORK, ASSIGNOR TO THE ROCHESTER SASH LOCK COMPANY, OF ROCHESTER, NEW YORK.

SASH-LOCK.

SPECIFICATION forming part of Letters Patent No. 685,700, dated October 29, 1901.

Application filed October 6, 1900. Serial No. 32,294. (No model.)

To all whom it may concern:

Be it known that I, FRANK BOGART TOWNSEND, a citizen of the United States, residing at Penn Yan, in the county of Yates and State 5 of New York, have invented a new and useful Sash-Lock, of which the following is a specification.

This invention relates to sash-locks, and more especially to that type of locks associated with a sliding window-sash and coöperating with a slide-rod or equivalent element to provide for securely and effectively locking the sash against movement in either direction at any point of elevation.

To this end the invention contemplates an improved type of sash-lock capable of application to either an upper or lower sash and so constructed that the entire lock may be seated flush within the stile or other part of 20 the sash to which it may be applied.

A further object of the invention is to provide an improvement in sash-locks of that type employing finger-controlled clutch-levers in which the levers shall be housed 25 throughout their entire length and will have no projection beyond the ends of the casing with which they are associated, so as to obviate the projection of the gripping ends of the levers beyond the sash-stile in front of the 30 window pane or glass, as is common in some types of locks—such, for instance, as in the sash-lock shown in my former patent, No. 561,927.

Another object of the invention is to provide a novel mounting and relative positioning of parts whereby the same shall be disposed in the most effective positions, while at the same time being capable of ready removal and replacing, and the invention also has in 35 view a novel form and mounting of holding-catch coöperating with the clutch-levers to hold them in their inoperative positions when it is desired to permit a free up-and-down movement of the sash to which the lock is 40 applied.

With these and many other objects in view, which will more readily appear as the nature of the invention is better understood, the same 45 consists in the novel construction, combination, and arrangement of parts hereinafter more fully described, illustrated, and claimed.

While the essential features of the invention are necessarily susceptible to some modification without departing from the spirit or scope thereof, still the preferred embodiment 55 of the improvements is shown in the accompanying drawings, in which—

Figure 1 is a perspective view of an improved sash-lock constructed in accordance with this invention shown applied to the 60 stile of a window-sash. Fig. 2 is a plan view of the lock with the cover-plate removed, showing in full and dotted lines the active and inactive positions of the finger-controlled clutch-levers. Fig. 3 is a sectional view on 65 the line 3-3 of Fig. 2. Fig. 4 is a detail in perspective of the casing with all of the parts removed therefrom. Fig. 5 is a detail in perspective of the holding-catch which coöperates with the clutch-levers for securing them 70 in an inactive position.

Like numerals of reference designate corresponding parts in the several figures of the drawings.

In carrying out the invention the working 75 parts of the lock are associated with a casing 1, which may be either cast or stamped from sheet metal at the option of the manufacturer. This casing is preferably of an approximately rectangular form and is constructed with a 80 box portion 2, usually of a substantially rectangular shape, and beyond said box portion 2, at one side thereof, with a housing extension 3, which extension coöperates with the box portion 2 of the casing to provide a complete inclosing case or housing for the finger-controlled clutch-levers to be presently referred to, thereby distinguishing the present invention from those structures in which the finger-engaged ends of the clutch-levers are 85 located outside of and wholly exterior to the casing which accommodates the working parts of the lock. The said housing extension 3, projected from one end of the box portion 2 of the casing, is preferably of an oblong form, being of a greater length than the width of the casing and, as shown in the drawings, is of substantially elliptical shape, with the end lobes 4 thereof projecting beyond the adjacent sides of the casing. The entire casing 90 is open at one side, which is necessarily the front side, on account of the position in which

- the lock is applied for use, and the said oblong housing extension 3 is designed to be left entirely uncovered or open, while the open side of the box portion 2 of the casing is adapted to be covered by the cover or face plate 5, secured on the retaining-lugs 6 and 7, projecting, respectively, from one end of the casing and the outer end of the post 8 offset from the base or closed side of the casing contiguous to the housing extension 3 thereof, said retaining-lugs 6 and 7 being upset in the usual manner after the cover or face plate is in position to provide for securing the same over the box portion of the casing.
- 15 In the present invention the cover or face plate 5 is provided at opposite side edges thereof with the offset perforated securing-ears 9, projecting beyond the plane of the adjacent sides of the casing and adapted to receive suitable fasteners 10, passing into the stile 11 of the window-sash to provide for holding the lock firmly in place. At this point it is to be observed that in applying the lock to the stile 11 or other point on the window-sash 20 the latter is formed with a mortise 12 of a depth equaling the depth of the casing 1 and conforming in shape thereto in order that the entire casing, including its oblong housing extension 3, may be fitted flush within the sash-stile, so that no part of the lock will project beyond the face of the sash a sufficient distance to interfere with the upper and lower sashes freely passing each other.
- 25 The box portion 2 of the casing 1 is provided in diametrically opposite sides thereof with the vertically-aligned rod-openings 13, adapted to loosely receive therein the slide-rod 14, arranged at the inner side of the window-frame 15 and adapted to lie in a groove 16, formed in the edge of the sash-stile for the reception thereof, said arrangement of the slide-rod being substantially the same as disclosed in my aforesaid patent. In addition to the diametrically opposite rod-openings 13 30 the casing 1 is provided, within the box portion 2 thereof at one side of the plane of said openings, with a transverse fulcrum bar or web 17, which is preferably formed integrally with the body of the casing, and is provided 35 with a pair of spaced bearing-slots 18, having rounded contact edges 19 and adapted to receive therein the intermediate portions of the pivotal finger-controlled clutch-levers 20, which are housed throughout their lengths in 40 the box portion 2 and housing extension 3 of the casing, said levers having no projection whatever at their ends beyond the end portions of the casing, as may be plainly seen from Figs. 1, 2, and 3 of the drawings. The 45
- 50 transverse fulcrum-bar 17, through the medium of the bearing-slots 18 thereof, constitutes a fulcrum or pivotal support for the levers 20, which are loosely arranged within said slots, being held in operative positions 55 therein through the medium of the cover or face plate 5, previously referred to. The terminals of the clutch-levers within the box

portion 2 of the casing are provided with engaging ends or ears 21, having perforations 22, receiving the slide-rod 14 and adapted to have a clutching engagement therewith, said levers when held at an angle being arranged to carry their clutch-openings 22 out of alignment with the axis of the rod 14, thereby providing the clutch engagement referred to. 70 The ends of the levers opposite their engaging ends or ears 21 are formed with finger-grips 23, consisting of offset flanges or plates working within the housing extension 3 of the casing and having a slight lateral projection therefrom to permit of ready gripping between the fingers of the hand to provide for oscillating the said levers upon their pivotal supports in the manipulation thereof, as will be readily understood. To insure the 80 normal separation of the gripping ends of the levers and the consequent clutching engagement of the ends or ears 21 with the slide-rod, a coiled pressure-spring 24 is interposed between said levers and one side of the fulcrum-bar 17, said spring being housed and confined within the space between the said fulcrum-bar and the offset supporting-post 18 of the casing, thereby being held against displacement as long as the cover or face plate 5 is in 90 position.

95 In the ordinary use of the window-sash—that is, to permit of the same being freely raised or lowered—it is desirable to hold the finger-controlled clutch-levers in an inactive 100 position; but in the present invention this is accomplished through the medium of a holding-catch 25 for the said levers. The construction and mounting of this holding-catch are simple and effective. The said catch is 105 supported upon the lug 7 between the same and the inner side of the cover or face plate 5, the said catch essentially consisting of a slidable fastening-plate 26, provided at one edge with an outturned finger-flange 27, offset laterally from the casing beyond one edge of the cover or face plate 5, so as to be conveniently exposed for engagement by the fingers to provide for drawing the plate into 110 locking engagement with the clutch-levers in 115 the manner to be presently explained. The said sliding fastening-plate 26 is also provided at an intermediate point between its ends with a longitudinally-disposed guide-slot 28, which loosely engages over the retaining-lug 7 at the outer end of the supporting-post 8, said slot and lug therefor serving to hold the plate to reciprocation in a fixed plane, thus insuring its positive engagement 120 with and disengagement from the clutch-levers. 125

130 At opposite sides of the plane of its finger flange and slot the fastening-plate 26 is provided in one edge thereof with the oppositely-located locking-notches 29, which are adapted to be carried into engagement with the contiguous edges of the offset portions of the finger-grips 23, which play within the housing extension 3 of the casing, when said fin-

ger-grips are drawn toward each other to provide for releasing their engaging ears from clutching engagement with the sliding rod 14. It will be observed that when the finger-grips 5 are thus moved together to carry the clutch-levers to inactive positions with reference to the slide-rod 14 it is only necessary to draw the holding-catch 25 out from beneath the cover-plate, so as to carry the notches 29 there- 10 of into engagement with said finger-grips, thus positively holding the clutch-levers in inactive positions, and when it is desired to release the levers, so that they can become active, the holding-catch is slid back beneath 15 the cover or face plate, whereupon the spring 24 separates the clutch-levers into their inclined active positions.

From the foregoing it is thought that the construction, operation, and many advantages 20 of the herein-described sash-lock will be readily apparent to those familiar with the art without further description, and it will be understood that various changes in the form, proportion, and minor details of construction 25 may be resorted to without departing from the principle or sacrificing any of the advantages of this invention.

Having thus described the invention, what is claimed as new, and desired to be secured 30 by Letters Patent, is—

1. In a sash-lock, the combination with the slide-rod, of a casing receiving the slide-rod therethrough, and a pair of finger-controlled clutch-levers, both arranged longitudinally 35 within the casing and housed throughout their entire length therein, said clutch-levers having terminal finger-grips exposed from one side of the casing contiguous to one end of the latter, substantially as set forth.
2. In a sash-lock, the combination with the slide-rod, of a casing provided with a covered box portion having oppositely-arranged rod-openings, and a housing extension projected beyond one end of said box portion, the cas- 45 ing being further provided with an interior transverse fulcrum-bar having bearing-slots, and an offset supporting-post spaced from said fulcrum-bar, a pair of clutch-levers loosely and pivotally mounted within the 50 bearing-slots of the fulcrum-bar and having perforated clutch ends coöperating with the slide-rod, and at their opposite ends provided with finger-grips disposed within the said

housing extension, and a pressure-spring interposed between the clutch-levers and con- 55 fined in the space between the fulcrum-bar and said post, substantially as set forth.

3. In a sash-lock, the combination with the casing, of a pair of clutch-levers coöperating with the rod, and a slidable holding-catch 60 mounted within the casing and arranged to move in and out of engagement with both clutch-levers, substantially as set forth.

4. In a sash-lock, the casing having an off- 65 set supporting-post and a cover-plate engag- ing with said post, a pair of clutch-levers, and a holding-catch slidably supported upon the said post beneath the cover-plate and having locking means coöperating with both clutch-levers, substantially as set forth. 70

5. In a sash-lock, the casing having an off- 75 set supporting-post, a pair of similar clutch- levers mounted within the casing and having finger-grip projections at one end, and a holding- catch consisting of a fastening-plate slid- ably mounted upon said supporting-post be- 80 neath the cover of the casing, and provided with an offstanding finger-flange, and at op- posite sides of the plane of said flange with locking-notches adapted to engage with said 85 finger-grip projections of the lever, substan- tially as set forth.

6. In a sash-lock, the combination with the slide-rod, of the casing, provided with an in- 85 terior transverse fulcrum-bar having bear- ing-slots, an offset supporting-post spaced from the said fulcrum-bar, a pair of clutch- levers loosely and pivotally mounted within the bearing-slots of the fulcrum-bar and hav- 90 ing clutch ends coöperating with the slide- rod, and at their opposite ends provided with finger-grips exposed outside of the casing, a pressure-spring interposed between the clutch-levers and held confined in the space 95 between the fulcrum-bar and said post, and a cover or face plate coöperating with the ful- crum-bar, post and the casing to hold the spring from displacement.

In testimony that I claim the foregoing as my own I have hereto affixed my signature in 100 the presence of two witnesses.

FRANK BOGART TOWNSEND.
